UNITED STATES PATENT OFFICE.

CHARLES A. GRIFFITH, OF KNOXVILLE, TENNESSEE.

DUMPING CAR.

1,426,729.

Specification of Letters Patent. Patented Aug. 22, 1922.

Application filed January 11, 1921. Serial No. 436,448.

To all whom it may concern:

Be it known that I, CHARLES A. GRIFFITH, a citizen of the United States, residing at Knoxville, in the county of Knox and State of Tennessee, have invented a new and useful Improvement in Dumping Cars, of which the following is a specification, reference being had to the accompanying drawing.

10 My improvement relates particularly to dumping cars of the type shown in my United States Patent No. 1,268,344 dated June 4, 1918, and in Patent No. 1,268,390 granted June 4, 1918 to Hugh W. Sanford. 15 The object of the improvement is to provide a car with bottom doors adapted to open and close in substantially the same way as that shown in the aforesaid patents but to provide different means of locking 20 the doors in their closed positions whereby the doors may remain entirely under the axles of the car.

The invention relates to the doors which form the bottom of the car and the means for locking the doors in the closed position.

In the accompanying drawings:

Figure 1 is an upright longitudinal section showing the car in engagement with the means for raising the bottom doors.

30 Figure 2 is a perspective view of the means for locking the doors closed.

Figure 3 is a perspective view of a slightly modified form.

Referring to said drawings: A A are 35 track rails resting on ties A¹. B B are ordinary car wheels applied to the ends of axles C C. D is the body of the car. D¹ is the side beam forming a portion of the car, the ends of which are joined to and stayed 40 by the bumpers D² and the end walls D³ of the body.

The end of the car at the right, as viewed in the drawings, is the forward end of the car and it is to be understood that the car 45 moves forward for dumping and for closing the doors after the load has been discharged from the car. The discharge is downward between the rails A, and the place at which the discharge is effected is 50 called the dumping station. Beneath the rails A the material discharged from the car may be received by a chute or another car or any other suitable device, not shown.

Three doors, E, E¹ and E², are placed in 55 series to form the bottom of the car. The present invention relates to the manner in

which the two doors E and E¹ are locked in closed position. The third or left hand door E² may if desired, be locked in position in identically the same manner as that shown in the aforesaid patents. In said 60 patents it will be noticed that the first two doors are moved upwardly so that their free ends are above the axles C and are supported by the hinged part of the succeeding door. In the present invention I provide an altogether different locking device which enables me to lock the door in its closed position without the necessity of the door projecting above the axles C of the 70 adjacent door whereby a longer door may be employed. To accomplish this, the free end of each door extends under the axle of the adjacent door. The said free ends of the doors are provided with locking means 75 which will now be described. The doors E and E¹ are provided with a hole as E³ which may, in the preferred embodiment, be made in a lug E⁴ fastened to the bottom plate of the door, while the end of the next 80 or following door which co-acts to lock the first door closed, is provided with a finger as F which may be riveted to the upper curved end of said door. There are preferably three lugs E⁴ and three fingers 85 F, one at each end and one in the center of the doors. It will be manifest that when the door having the three fingers F turns on its axle, or on its pivot or hinge, the said three fingers F of one door are withdrawn from the holes E³ in the lugs E⁴ of the other or first door and the latter is allowed to drop to dump its load. After all 90 the doors are released and the material in the car completely dumped, the car doors are automatically re-set by contact with cam member A² in the same manner as that described in the aforesaid patents, the forward door being turned into the closed position and the next door being then 100 turned into closed position, whereby the meeting edges of said doors are interlocked, and the third door being then turned into the closed position, whereby the meeting edges of the second doors are interlocked and the rear edge of the third door is engaged by any suitable latch mechanism as, for example, the latch mechanism of the above-mentioned patents.

In lieu of the finger and hole arrangement shown in Figure 2, I may employ the construction shown in Figure 3 in which

hook-formed members as G are employed in place of the lugs E⁴ of Figure 2. When the rear door is turned upward, its forward edge moves downward and enters or interlocks with the hooks, G. Reinforcing members, H, are placed on the rear door outside of the places which will be engaged by the hooks. The function of the members, H, is to strengthen the edge of the rear door. It is to be observed that the members G and H are used merely for the purpose of strengthening the edges of the doors. If the edges of the doors are in themselves heavy enough to provide the required rigidity, the members G and H will not be needed. The essential consideration is that the rear of the meeting edges of two doors be turned downward below its hinge line and that the other of said edges be turned upward and that one of said meeting edges be of hook-form and that the other of said edges be formed for inter-engagement or inter-locking with said hook-form edge.

I claim as my invention:

1. The combination with a car body, of two doors having their forward parts hinged on lines which are horizontal and transverse to the length of the car body and the forward of said doors having its rear edge meeting the forward edge of the other door, and the rear of said meeting edges being turned downward below its hinge line and the other of said edges being turned upward, and one of said meeting edges being of hook-form, and the other of said edges being formed for inter-locking with said hook-form edge, substantially as described.

2. The combination with a car body and axles supporting said body and wheels supporting said axles, of two doors one of which has its forward part hinged to one

of said axles and the other of which has its forward part hinged on a line which is parallel to said axle and the forward of said doors having its rear edge meeting the forward edge of the other door, and the rear of said meeting edges being turned downward below its hinge line and the other of said edges being turned upward, and one of said meeting edges being of hook-form, and the other of said edges being formed for inter-locking with said hook-form edge, substantially as described.

3. The combination of a car body, axles supporting said body for maintaining horizontal position and movement of said body, wheels carrying said axles, the first bottom door hinged near its forward edge on a line which is horizontal and transverse to the length of the car body, and having a curved locking device at its edge, and a second door having a curved member provided with a lug co-acting with the said curved locking device below the axle of the car, substantially as described.

4. The combination of a car body, axles supporting said body for maintaining horizontal position and movement of said body, wheels carrying said axles, a first bottom door hinged near its forward edge on a line which is horizontal and transverse to the length of the car body, and having a curved locking device at its edge having a hole therein, and a second door having a finger adapted to enter the hole in the curved locking device of the first door as said second door is swung upward on its axis, substantially as described.

In testimony whereof I have signed my name, this 8th day of January, in the year 1901 thousand nine hundred and twenty-one.

CHARLES A. GRIFFITH.
